UNITED STATES PATENT OFFICE.

GARDNER T. VOORHEES, OF BOSTON, MASSACHUSETTS.

DEVICE FOR PREVENTING VAPOR FROM PASSING THE EXPANSION-VALVES OF REFRIGERATING-MACHINES.

SPECIFICATION forming part of Letters Patent No. 731,824, dated June 23, 1903.

Application filed August 30, 1901. Serial No. 73,814. (No model.)

To all whom it may concern:

Be it known that I, GARDNER T. VOORHEES, a citizen of the United States, residing at Boston, in the county of Suffolk and State of Massachusetts, have invented certain new and useful Improvements in Devices for Preventing Vapor from Passing the Expansion-Valves of Refrigerating-Machines, of which the following is a specification, reference being had therein to the accompanying drawing.

The drawing shows a diagrammatic view of a refrigerating-machine provided with my invention.

It is a well-known fact that ammonia gas or vapor is very likely to be formed in what is known as the "liquid-pipe" connecting the condenser and cooler of a refrigerating-machine, the formation of said gas being due, for example, to one or more of such causes, as the exposure of the liquid-pipe to a temperature hotter than that of the condenser water, to a lower pressure in the liquid-pipe than that in the condenser, or to heat generated by friction due to the flow of the ammonia in the liquid-pipe. Should said gas or vapor pass the expansion-valve of the machine into the cooler, it is equally clear that the ammonia gas or vapor would not only do practically no cooling, thus greatly reducing the capacity of the machine, but would require just as much work on the part of the compressor (or absorber and generator, in case they are employed,) to return the gas to the condenser.

Now it is the principal object of my invention to provide means whereby nothing but refrigerant liquid free from vapor or gas can pass the expansion-valve of a refrigerating-machine.

Said invention consists in providing means (such, for example, as an escape-pipe) so located in relation to the condenser and the expansion-valve of the machine that any ammonia-gas that may be in the liquid-pipe will return through said escape-pipe to a condenser rather than pass through the expansion-valve to the cooler.

Said invention further consists in providing apparatus whereby said means may be used in connection with an expansion-valve located above the condenser.

In the drawing illustrating the principle of my invention and the best mode now known

to me of applying that principle I have shown its application to a refrigerating-machine in which there are two expansion-valves, one being above the level of the condenser and another below. For the sake of clearness I will first describe that construction in which the expansion-valve is below the condenser, so that the ammonia by reason of its own head flows to the expansion-valve.

A is a condenser, and B a gas-trap. A liquid-pipe 1 2 3 4 5 leads from the bottom of the condenser A downwardly to the gas-trap B, whose flow area is larger than that of said liquid-pipe, while from the top of the gas-trap B an escape-pipe 6 7 23 leads upwardly and opens into the condenser. A pipe 17 18 19, provided with an expansion-valve v, connects the bottom of the gas-trap B with a cooler D, that has a brine-coil d d' passing through it. A compressor E is in communication with the cooler D by means of a pipe 20 21 and with the condenser A by a pipe 22 23. The operation of this form of my invention is as follows: The ammonia-gas (indicated in the drawing by dots) is delivered by the compressor E to the condenser A and is here condensed by the cooling-coil a a'. The liquid ammonia thereby formed collects in the bottom of the condenser or its equivalent and flows out of the condenser A and then downwardly through the liquid-pipe 1 2 3 4 5, where the liquid ammonia is likely to become partially vaporized by any of the above-mentioned causes. The liquid and any vapor there may be are then delivered to the gas-trap B, which by reason of its having a larger flow area than the liquid-pipe sufficiently stops the flow of the liquid and gaseous ammonia to permit the latter to rise through the escape-pipe 6 7 and recondense in the cooler atmosphere in the condenser A. All the ammonia gas or vapor that entered the gas-trap B having returned by the escape-pipe 6 7 to the condenser A, only liquid ammonia enters the pipe 17, goes by the expansion-valve V, and enters by means of pipe 18 19 the cooler D, where it is evaporated by the heat of the brine-coil d d' and converted to gas, which flows through pipe 20 21 to the compressor E. The latter then forces the gas to the condenser A, and the cycle of operations is thus completed.

The operation of my device now being clear, I will proceed to describe the embodiment of my entire invention in an apparatus shown in the drawing above that portion thereof 5 already described, said apparatus having its expansion-valve located at a level above that of the condenser A.

A pipe 1 2 8 9 leads upwardly from the bottom of the condenser A and opens into 10 an auxiliary condenser C, provided with a cooling-coil c c'. A liquid pipe 10 11 12 13 forms communication between the condenser C and a gas-trap B', whose flow area is larger than that of the pipe 10 11. From 15 the top of the gas-trap extends an escape-pipe 14 15 16, which opens into the auxiliary condenser C above the level of the liquid ammonia therein. A pipe 24 25 connects the bottom of the gas-trap B' with a cooler D' 20 and is provided with an expansion-valve V'. The cooler D' has a brine-coil d² d³ and also a pipe 26 27, which opens into pipe 21. The temperature and pressure in the auxiliary condenser C being less than in the condenser 25 A, the liquid ammonia rises through the pipe 2 8 9 and flows into the auxiliary condenser C, where any ammonia-gas that may have been formed in the pipe 2 8 9 is condensed. The liquid ammonia now flows through the 30 pipe 10 11 and passes into the gas-trap B'. If for any reason ammonia-gas enters the trap, it immediately rises in the pipe 14 15 16 and is condensed in the auxiliary condenser C. It will here be noticed that the auxiliary condenser C, the gas-trap B', and their connections are like the condenser A, the gas-trap B, and their connections. The liquid ammonia in the gas-trap B' then flows through pipe 24, past the expansion-valve V', and into the 35 cooler D', where it is vaporized by the heat given off by the brine-coil. The resulting gas passes off through pipe 26 27 to the compressor, which in turn forces it along through pipe 22 23 into the condenser A. 40

45 It will be plain to all skilled in the art to which this invention appertains that my invention may be embodied in many different forms without departing from the spirit thereof, and I do not limit myself to any particular form of cooler, compressor, or condenser.

In short, my invention consists in means whereby the gas of a refrigerant liquid about to pass an expansion-valve is allowed to escape from rather than flow with said liquid 50 through said valve.

What I claim is—

1. In a refrigerating apparatus employing a liquid which is alternately vaporized and condensed, the combination with a condenser, 55 of a cooler; a liquid-pipe leading from the condenser to the cooler; a throttling device

in said liquid-pipe; a trap device located in said liquid-pipe and between the condenser and said throttling device; a gas and vapor pipe communication leading directly from 65 said cooler to said condenser; means of compression located in said gas or vapor pipe to raise the pressure of the gas or vapor from the cooler, from that of the cooler to that of the condenser; and a pipe in direct and open 70 communication between said trap and that portion of said gas and vapor pipe, on the compression side of said means of compression.

2. In a refrigerating apparatus employing 75 a liquid which is alternately vaporized and condensed, the combination with a condenser; of a cooler; a liquid-pipe leading from the condenser to the cooler; a throttling device in said liquid-pipe; a trap device, located in 80 said liquid-pipe, and between the condenser and said throttling device; gas and vapor pipe communication between said cooler and said condenser; means of compression, located in said gas or vapor pipe, to raise the 85 pressure of the gas or vapor from the cooler, from that of the cooler to that of the condenser; a pipe, independent of the said liquid-pipe from the condenser to the cooler, leading from the trap device, and in direct 90 communication with the compression side of said means of compression.

3. In a refrigerating apparatus, the combination of a condenser; an auxiliary condenser; a pipe connecting said condensers; a 95 gas-trap; a pipe communicating between said auxiliary condenser and said gas-trap; a pipe leading from the top of said gas-trap and opening into said auxiliary condenser above the level of the refrigerant liquid therein; a 100 cooler; a pipe leading from the bottom of said gas-trap to said cooler; a throttling device in said pipe and located above the level of the condenser, but below that of the auxiliary condenser; means to convey the refrigerant 105 vapor from the cooler to the condenser; and means to raise the vapor-pressure from the cooler, to that required in the condenser.

4. The combination of a condenser; a gas-trap below said condenser; a liquid-pipe communicating between said condenser and said gas-trap; an escape-pipe leading from the gas-trap and opening into the condenser; and a throttling device in a pipe leading from the gas-trap to a cooler; said throttling device being below said condenser. 110 115

In testimony whereof I affix my signature in presence of two witnesses.
